N. M. ELTON

BABY CRAWLER

Filed June 6, 1925

INVENTOR:
NINA M. ELTON;
By G. E. Maynard
Att'y.

UNITED STATES PATENT OFFICE.

NINA MAY ELTON, OF LOS ANGELES, CALIFORNIA.

BABY CRAWLER

Application filed June 6, 1925. Serial No. 35,381.

To all whom it may concern:

Be it known that I, NINA M. ELTON, a citizen of the United States, and resident of Los Angeles, Los Angeles County, State 5 of California, have invented new and useful improvements in a Baby Crawler, of which the following is a specification.

This invention relates to baby vehicles and has for its object to provide a device which 10 is designed to keep babies, from six months to a year and a half old, from crawling on their stomachs over floors or other plane surfaces. Thus the primary object of the device is to protect the baby's health by 15 keeping its clothes sweet and clean but allowing the baby to have beneficial and developing exercise by use of its arms and legs to propel the crawler over the floor with ease and safety.

20 An object is to provide a baby or "kiddie" crawler of such construction and design that the baby's fingers, hands, toes and legs will be protected from being run over by the rollers or casters of the device.

25 Several other objects and advantages will be made manifest in the following specification of illustrated embodiments of the invention herewith; it being understood that modifications, variations and adaptations 30 may be resorted to within the spirit and scope of the invention as it is here claimed.

Figure 1 is a perspective of the preferred form of the crawler.

Figure 2 is a side elevation of it.

35 Figure 3 is a plan showing the disposition of the rollers.

Figures 4 and 5 show figured head ends on the crawler.

The crawler comprises a preferably flat 40 bottom board or plank 2 having a reduced or narrowed end 5 thus forming reentrant arm spaces 4 so that a baby lying on the board could thrust his arms and hands down within the extreme side edges, the infant's shoulders being disposed about at the neck 5.

To prevent the baby from rolling off the board 2 this has perpendicular side guards 7 extending from the front corners at the neck 5 of the board and back of the baby's 50 shoulders.

At the rear end of the guards 7 the board is cut sharply in at 8 and forms a nar-

row tail part 9 over the side edges of which the baby's legs may comfortably hang to reach the floor and be worked to propel the 55 crawler.

The front end of the crawler is elevated and supported by a pair of swivel rollers or castors 10 spaced well in from the edges of the crawler so that the baby's fingers can- 60 not be caught and run over.

The rear end of the crawler is supported on a central trailing roller 11.

I prefer that the head and tail ends of 65 the crawler be rounded off as shown in Fig. 1, but the head and tail parts may be variously shaped and decorated as in Figs. 4 and 5.

If desired a fastening girdle 12 attached at 13 to the board may be secured around 70 the baby's body, or a strap 14 Fig. 4 drawn over its shoulders and fastened to buckles 15.

The crawler can be adapted for locomotive use by weak or crippled individuals.

The rounded corners of the bottom serve 75 to prevent marring of objects which may be struck and serve to easily deflect the crawler in glancing blows.

What is claimed is:

1. A baby crawler comprising a bottom 80 member having upright side guards to keep a baby in place on its stomach; the front and the rear ends of the said member being sharply inwardly recessed at the margin to form arm and leg spaces at the ends of the 85 guards to enable foot and hand propulsion.

2. A baby crawler comprising a bottom member having upright side guards to keep a baby in place on its stomach; the front and the rear ends of the said member being 90 sharply inwardly recessed at the margin to form arm and leg spaces at the ends of the guards to enable foot and hand propulsion, the trailing end of the crawler having a central castor roller, and a pair of front 95 rollers spaced in such a position from the front edges of the bottom member as to prevent catching the baby's fingers.

3. A baby crawler having a flat bottom board with sharply incurved front corners 100 extending to a rounded leading end over the sides of which the baby's arms may be passed down to a floor surface, and the rear end of the bottom board also being sharply

inwardly curved to form leg spaces, and upright side guards from the front to the rear corners of the recesses.

4. A baby crawler comprising a bottom member having upright side guards to keep a baby in place on its stomach; the front and the rear ends of the said member be-

ing sharply inwardly recessed at the margin to form arm and leg spaces at the ends of the guards to enable foot and hand propulsion and means, fastened to the bottom of the crawler, to be passed over the baby to secure it in place.

10

NINA MAY ELTON.
